UNITED STATES PATENT OFFICE.

GUSTAV STRANDT, OF MILWAUKEE, WISCONSIN.

BOTTLE-CAPPING MACHINE.

1,221,105.

Specification of Letters Patent. Patented Apr. 3, 1917.

Application filed May 26, 1913. Serial No. 769,802.

To all whom it may concern:

Be it known that I, GUSTAV STRANDT, a citizen of the United States, residing at Milwaukee, county of Milwaukee, and State 5 of Wisconsin, have invented new and useful Improvements in Bottle-Capping Machines, of which the following is a specification.

My invention relates to improvements in that class of bottle-capping machines for 10 which Letters Patent No. 1,040,453 in the United States were issued to me October 8, 1912, and, like the capping machine, shown and described in said application, it includes a device for delivering the cap to a bottle 15 which is dependent for its action upon the resistance of a bottle in position to be capped. In other words, unless a bottle is in place to receive a cap, no cap will be discharged from the machine.

20 My present improvements pertain more especially, among other things, first, to the construction of the reciprocating slide by which a cap is conveyed from the cap receptacle to the place of discharge above the 25 bottle to be capped; second, to the device for yieldingly resisting the upward movement of the plunger and plunger-inclosing sleeve as they are together raised preparatory to receiving a bottle; and third, to the 30 peculiar construction of the cap-supporting collar whereby it is adapted to support each cap successively in a true horizontal position above and parallel with the bottle-supporting seat; also to the device for delivering the cap slightly below the upper 35 end of the bottle preparatory to being forced into such seat.

My device is further explained by reference to the accompanying drawings, in 40 which—

Figure 1 is a plan view thereof.

Fig. 2 is a side view.

Fig. 3 is a front view.

Fig. 4 is a side view, part in vertical 45 section.

Fig. 5 is a side view, part in section, of one of the spring-actuated stops, and

Fig. 6 is a transverse vertical section of 50 one of the reciprocating slides and its supporting guide ways.

Like parts are identified by the same reference numerals throughout the several views.

1 represents a milk bottle of ordinary 55 construction in position to be capped. The

movable parts of the capper are supported from the shaft 7.

While my improvements are adapted to be used for capping either a single bottle or any desired number of bottles at a time, 60 the same is, for brevity of description, shown and described as adapted to cap two bottles at a time.

4, 4 represent the mouth pieces of the capper, which are adapted to inclose the 65 upper ends of the bottle as the same are being capped. 5, 5 are chambers for the reception of the plungers 6, 6. 9, 9 are plunger-supporting shafts. 8 is a cross head. 12, 12 are receptacles for the reception 70 of the caps 13. 14, 14 are platforms upon which the caps 13 are supported preparatory to being forced into the mouths of the bottles. 15, 15 are reciprocating 75 slides by which the caps are successively brought into place above the bottles to be capped. 17, 17 are spiral springs through which a yielding movement is communicated from the cross head 8 to the cap-actuating slides 15 through the collars 18, 80 arms 19, pivotal bolts 20, links 21, pivotal bolts 22, arms 23 and 24, pivotal bolts 25, pins 25', links 26, and pivotal bolts 26'.

The receptacles 12 are supported from the sides of the chambers 5 at a slight distance 85 above the platforms 14, whereby a sufficient space is provided between the lower ends of the receptacles 12 and the platforms 14 for the movement of the reciprocating slides 15, by which the paper caps are moved from 90 the receptacles 12 beneath the plungers 6 preparatory to being forced into the mouths of the bottles.

In operating the device the spiral springs 95 17 are compressed by the downward movement of the shaft 7 until the tension of such spring exceeds the resistance of the caps, when said caps will be forced by the tension of such spring into the mouth of the bottle. The paper caps are supported above 100 the bottles on the downwardly converging annular flanges 27 within one of the annular grooves 27'. Motion is communicated from the shaft 7 to the reciprocating slides 15 through the mechanism previously described, whereby said slides are forced back 105 from the position shown in Fig. 2 to the outer ends of the platforms 14 preparatory to engaging the next succeeding cap above.

Thus it is obvious that by the downward 110

movement of the actuating means, a paper cap is forced into the mouth of the respective bottles while the cap operating slides are simultaneously thrown back preparatory to engaging the next succeeding cap, while by the upward movement of said vertically moving shaft 7, the cap actuating slides are thrown, by the action of said coöperating parts, in the opposite direction, whereby other caps are brought beneath the plungers 6, preparatory to being forced into the mouths of the bottles by the next succeeding downward movement of said vertically moving shaft 7.

15 The annular grooves 27' are formed for the reception of the paper caps as they are successively brought into place, and the object of such grooves is to hold each cap in a true horizontal position, parallel with the 20 mouth of the bottle, whereby all parts of the periphery of the caps are simultaneously brought into the seats of the bottles.

The downwardly converging flange 27 is adapted to extend into the mouth of the 25 bottle a slight distance as the mouth piece 4 engages the exterior surface of such bottle, whereby the liability of the caps being accidentally forced to one side of their seats in the neck of the bottle is avoided. It will 30 be understood that the capper is adapted to be adjusted to bottles of two or more different heights, that, when capping bottles of the greatest height, it is adjusted as shown in Figs. 2 and 4, whereby the mouth 35 piece 4, plunger 6 and other coöperating parts, which are suspended from the cross head 8, are supported from the upper notch 11', formed in the vertical shaft 7. When, however, shorter bottles are being capped, 40 such parts are supported from the notches 12'' and 13'' of said shaft.

Preparatory to adjusting the cross head 8 higher or lower on said shaft 7, the set screws 6' are turned back out of impinging 45 contact with the standards 8'. When this is done, the clamping bolt 14'' is turned up slightly in its bearings, whereby the supporting plate 15' is free to be moved back 50 out of the notch 11', when the cross head 8 and the parts suspended therefrom may be raised or lowered to conform to the height 55 of the bottles which are being capped, when the plate 15' is moved back into engagement with one of said notches. When 60 the parts have been thus adjusted, the plate 15' is secured in place by turning down the clamping screw 14'' in its bearings. The plate 15' is provided with an elongated slot 16' for the reception of the guide screw 18', which elongated slot 16' permits of the required adjustment of said supporting plate 15'. When the cross head 8 has been 65 thus adjusted to conform to the height of the bottles which are being capped, the set screws 6' are again turned forward in their

bearings until their inner ends are brought into impinging contact with said vertical posts 8'.

As the apparatus is being moved upwardly by the upward movement of the 70 vertical shaft 7, the shoulders 31, formed in the exterior wall of the chamber 5, are brought into contact with the yielding stops 32, and said stops serve to gradually arrest the upward movement of such parts. The 75 stops 32 are supported from the yoke 9' through the horizontal plates 33, which plates are rigidly connected with said yoke in any convenient manner. The stops 32 are connected with said plates 33 through 80 the vertical sleeves 34 and the spiral springs 35. The springs 35 are interposed between the upper ends of said stops and the upper ends of said sleeves, whereby the jar or shock, which would otherwise occur when 85 the moving parts of said apparatus are brought to the limit of their upward movement, is resisted by the yielding movement of said spiral springs.

The stops 32 are retained in place beneath said spiral springs by the central vertical members 36, which members 36 extend through apertures 36', provided therefor, in the top of the sleeves 34, and are provided with nuts 37, by which they are secured in place in said sleeve. Thus it is obvious that, as the capper moves upwardly, the shoulders 31 will be brought into contact with the lower ends of said yielding stops 32, whereby the spiral springs 35 are slightly compressed, when, with the downward movement of the capper, said stops 32 are thrown down, by the recoil of said springs until the nuts 37 are again brought into contact with the top of said sleeves. 100

By the device shown in my said prior patent, the arms 24 were connected with the reciprocating slides 15 by simply inserting the lower ends of said arms 24 through apertures provided therefor in the respective sides of said slides 15, while, by my improved form, the member 40 serves as a rigid support for the pivotal bolts 26', through which said slides are connected with the lower ends of the arms 24, as previously described. Said reciprocating slides 15 are rigidly connected with the reciprocating member 40 by a plurality of bolts or rivets 41. The member 40 serves to reinforce and stiffen the reciprocating slides, while it also partially surrounds and engages the vertical sides and a portion of the bottom of its supporting platforms 14, as shown in Fig. 6, whereby it becomes impossible for the slides 15 to move vertically 110 from or laterally upon its supporting platform. 115

The cap receptacles 12 are each provided with vertical slots 12' for the reception of the handles 13' of the weights 14', while 120

said slots 12' also enable the operator to see the paper caps and to ascertain when the supply has been exhausted. The object of the weights 14' is to hold the caps in place 5 and force them down upon the supporting platforms as they are successively withdrawn from the receptacles by the reciprocating slides, while the handles 13' protrude through said slots in such a manner 10 as to enable the user to readily grasp the same when desirous to remove the weights for the purpose of replenishing the receptacles with caps.

Having thus described my invention, 15 what I claim as new and desire to secure by Letters Patent is:

1. The combination with the actuating member of a bottle capper, of a cap retaining mouth piece provided with a plurality 20 of annular grooves for the reception of the caps, said grooves being adapted to hold

said caps in a proper position to enter the mouths of the bottles.

2. In a bottle capping machine of the described class, the combination of a vertical 25 shaft, provided with a plurality of transverse notches for the reception of the end of a supporting plate, a cross head connected with said vertical shaft, a plate provided with an elongated slot slidably supported 30 on said cross head, means for slidably securing said plate to said cross head, whereby the latter may be moved horizontally and caused to engage any one of the notches in said vertical shaft, all substantially as 35 and for the purpose specified.

In testimony whereof I affix my signature in the presence of two witnesses.

GUSTAV STRANDT.
